Patented Nov. 25, 1919.

UNITED STATES PATENT OFFICE

MATTHIAS S. YEAGER, OF LOS ANGELES, CALIFORNIA, ASSIGNOR TO LIBERTY BURNER CO., A CORPORATION OF CALIFORNIA.

GENERATOR.

1,323,140.

Specification of Letters Patent. Patented Nov. 25, 1919.

Application filed September 11, 1918. Serial No. 253,505.

To all whom it may concern:

Be it known that I, MATTHIAS S. YEAGER, a citizen of the United States, residing at Los Angeles, in the county of Los Angeles 5 and State of California, have invented new and useful Improvements in Generators, of which the following is a specification.

This invention relates more particularly to that type of generators commonly used 10 in the generation of gases from liquid fuels for use in connection with hydro-carbon burners.

A prime object of my invention is to provide a liquid fuel generator construction 15 that will efficiently remove carbon deposits or foreign matter deposited therein during its operation.

A further object is to provide a generator construction which is provided with means 20 for evenly distributing the hydrocarbons in thin films on its passage therethrough, thereby greatly promoting instantaneous vaporization.

A still further object is to provide a generator construction in which the pressure of 25 the gases formed during its operation will control the supply of fuel delivered thereto.

Other objects and advantages will appear 30 from the following description, reference being had to the accompanying drawings forming a part of the specification, in which:

Figure 1 is an enlarged central vertical section through my improved generator.

Fig. 2 is a cross sectional view taken on line 2—2 of Fig. 1 looking in the direction indicated by the arrows thereon.

My improved generator is illustrated in a greatly enlarged form in the drawing so 40 as to bring out more clearly the details of construction, the diameter of the casing or tube in general practice preferably not being of a greater diameter than one-half inch.

The generator 5 preferably consists of a 45 cylindrical tube or casing 6 of any desired length to suit the configuration of the burner to which the generator is applied. On its discharge end it is provided with a 50 plug 7 having a gas outlet orifice 8 therein, the inner surface 9 of the plug being cone-shaped, as illustrated, so as to form a seat for the valve closure which will be more particularly described hereinafter. The 55 outer or control end of the generator is pro-

vided with a closure cap 10 which forms a part of the packing gland 11 of usual construction. Cap 10 is provided with a fuel inlet nipple 12 which is secured to one end of a fuel pipe line (not shown).

Mounted within the generator casing is a cylindrical rod 13 having a reduced outer end 14 provided with a seat, and gas regulating conical pin 15 adapted to partially enter the gas outlet orifice 8 in the plug 7. 60 The outer end of reduced portion 14 is adapted to bear against the conical seat 9 of plug 7, and the pin 15 is for the purpose of regulating the area of the outlet orifice 8, and at the same time furnishing a means 65 for cleaning the orifice during the operation of the burner.

The end of rod 13 opposite reduced portion 14 is also provided with a reduced portion 16 which passes through the packing 70 gland 11 and forms a stem of the valve, the end of reduced portion 15 being provided with a hand wheel 17 so that the rod or valve closure may be rotated to open or close the gas outlet orifice 8.

In order to provide a means for removing the carbon deposits formed by the combustion of the fuel passing into the generator, and at the same time to distribute the fuel in a thin film so that it may be instantly 75 vaporized on its passage therethrough, I have provided a cylindrical sleeve 18 preferably formed of asbestos or other similar fire resisting materials. This asbestos sleeve is secured at its ends to the reduced 80 portions 14 and 16 by means of wire wrappings 19 or other suitable securing means.

By covering the rod 13 with an asbestos covering which closely fits the interior diameter of tube or casing 6, all deposits of 85 carbon formed during the operation of the burner may be readily loosened from the interior peripheral surface of the casing on a rotation of the rod 13, the same after being loosened being blown out by the pressure 90 of gas through outlet orifice 8 and completely consumed in the burner to which the burner is attached. I have here shown my improved generator in the position it will assume when mounted on a hydro-carbon burner, which is shown in this instance as consisting of an upper portion 20 of a burner head which is provided with flame slots 21, the flames impinging directly against the under portion of the generator 95 100 105 110

tube or casing 6. The burner head is provided with a vertical apertured wall 22 in which is mounted one end of the generator 5, while diametrically opposite is another 5 apertured wall 23 in which is mounted the other end of the generator, a set screw 24 providing for a longitudinal adjustment of the burner to form the gas mixing chamber 25. By means of this longitudinal adjustment of the generator I am enabled to 10 form a perfect mixture of the gas and air before its entrance into the burner head.

It will be seen from the above description that I have provided a gas generator 15 that will prove extremely efficient in connection with hydro-carbon burners, and that all carbon deposits formed therein may be quickly loosened and blown from the generator without the necessity of disman- 20 tling the same.

It will be further noted that by utilizing the outer reduced end of rod 14 as a closure for the outlet orifice 8, instead of employing the pin 15 as a closure as is common in 25 most constructions, that an operator can readily unseat the valve closure and that

there will be no danger of the pin sticking in the orifice and becoming broken in efforts to remove the same. The pin 15 also controls the area of the outlet orifice 8 so 30 that the proper amount of gas can be minutely regulated.

What I claim is:

In a device of the class described, a cylindrical casing provided on one end thereof 35 with a gas outlet orifice, and on its opposite end with a closure cap having a fuel inlet opening, a valve rod having an enlarged portion mounted within said casing, a tube of fire resisting material surrounding said 40 enlarged portion and contacting with the inner wall of said cylindrical casing, and means for securing the ends of said tube to the smaller portion of the valve rod, whereby the tube will be held firmly against 45 either longitudinal or rotary movement on said stem.

In witness that I claim the foregoing I have hereunto subscribed my name this 9th day of August, 1918.

M. S. YEAGER.
